(57) CLAIM

The ornamental design for a neck support for a shampoo bowl as shown and described.

DESCRIPTION

FIG. 1 is a top perspective view of a neck support for a shampoo bowl showing my design;
FIG. 2 is a front view thereof;
FIG. 3 is a right view thereof;
FIG. 4 is a left view thereof;
FIG. 5 is a top view thereof;
FIG. 6 is a bottom view thereof;
FIG. 7 is another front view thereof; and,
FIG. 8 is a cross-sectional view of the neck support for a shampoo bowl taken along the line 8-8 in FIG. 7.
The broken lines show portions of the neck support for a shampoo bowl that form no part of the claimed design.
The dot-dot-dash lines in FIG. 7 show the axis of the line 8-8 in which the cross-sectional view of FIG. 8 is taken from and form no part of the claimed design.
